CHIP BREAKING ATTACHMENT FOR
DRILLING MACHINES.Milton C. Taylor, Chicago, Ill., assignor, by mesne
assignments, to Ex-Cell-O Corporation, Detroit,
Mich., a corporation of Michigan.

Application September 17, 1945, Serial No. 616,801

10 Claims. (Cl. 77—5)

1

The present invention relates to the art of drilling a hole in machinable materials such as metals, alloys, elastomers and plastics which is usually done with twist drills or the like and more particularly to an improved construction for accomplishing the Karweit drilling process described in application Serial No. 484,612 filed April 26, 1943, now Patent Number 2,453,136, reference to which is hereby made for a further explanation of the Karweit process, which briefly stated, is a process in which a drill such as used in the metal and plastic art is repeatedly oscillated within a minor portion of a revolution once approximately each revolution of the drill to comminute the chips so that they will pass out of the flutes of the drill quite easily without scoring the side walls of the cut or packing in the flutes.

The present invention is also an improvement in certain respects upon my earlier application Serial No. 572,710 filed January 13, 1945 relating to the same subject matter, reference to which is hereby made for a detailed discussion of the merits and results obtained by using a planetary type driller to time the frequency of oscillation in stepped relationship to the rotation of the drill whereby the oscillation can be arranged to occur once approximately every three revolutions or at any other ratio desired within the limits of the Karweit process.

One of the objects of the present invention is to provide an improved arrangement for oscillating the drill during a feed traverse thereof, in which the rolling parts of the oscillator carry only a part of the feed load developed in feed traversing the drill throughout its cycle of operation.

Another object of the invention is to utilize the effect of centrifugal force to augment the resilient means by which a cam and follower of the oscillator are urged into engagement at the higher speeds at which the follower is more likely to float without following the relief contour of the cam.

A further object of the invention is to provide a driller of the type herein described which can be readily changed to vary the frequency of operation in relationship to drill rotation as by changing the gear ratio which controls the frequency of operation, or, by eliminating a gear drive entirely.

Another object of the invention is to provide an improved construction in which moments of inertia force involved in oscillating a drill to perform the Karweit process are balanced against

each other to reduce oscillation or hammering of the spindle bearings of the drill press.

A further object of the invention is to provide an improved construction to perform the Karweit drilling process which is inexpensive to operate, service and maintain and easily comprehended and used by drill press operators.

These being among the objects of the present invention other and further objects will become apparent from the drawings, the description relating thereto and the appended claims.

In the drawings:

Fig. 1 is a side elevation of a hand feed drill press upon the quill of which any one of the embodiments described herein is mounted.

Fig. 2 is an enlarged vertical section of the device shown in Fig. 1 illustrating one form of the invention.

Fig. 3 is a section taken upon the line 3—3 in Fig. 2.

Fig. 4 is a section taken upon the line 4—4 in Fig. 2.

Fig. 5 is an enlarged vertical section similar to Fig. 2 illustrating another form of the invention.

Fig. 6 is a section taken upon the line 6—6 of Fig. 5.

Fig. 7 is an enlarged vertical section taken of a driller similar to the form shown in Figs. 1 and 5 illustrating another form of the invention which can be used for high speed drilling with drills smaller than $\frac{1}{4}$ ".

Fig. 8 is a plan view of the device illustrated in Fig. 7, and

Fig. 9 is a plan view of the improved vane and follower carrier shown in Fig. 7 for dissipating heat developed by the embodiment shown in Fig. 7 when operating at high speeds.

Although various means have been employed heretofore to accomplish the Karweit process of 40 drilling a stringy material with a twist drill, all of them have virtually involved rolling a follower in a circular path upon a flat or planar cam surface. With these constructions, centrifugal thrust upon the followers, which have been rollers or frictionless bearing elements, has caused wear and developed heat particularly when subjected to the heavy loads that are carried by the cam and follower arrangement in transmitting the feed thrust from the drill spindle to the drill.

Furthermore, with the arrangement heretofore employed the rolling elements of the followers have preferably been rounded to reduce the scuffing effect experienced with a cylindrical tread surface rolling in a curved path on a planar surface. With the rounded roller the pressure

factor per square inch contact was quite high and excessive loading of the driller by inexperienced operators became a problem because of the extra heat generated and the excessive wear incurred due to this abuse and also the failure of the operator to keep the device properly lubricated.

Not only this, but a spring strong enough to assure that the follower would follow the relief in the cam at high speeds would be an unnecessary additional load upon the cam and follower arrangement at lower speeds.

In the present invention these problems have been overcome by rotating cylindrically treaded followers inside of and against a cylindrical cam path so that the load factor per square inch is lowered by distribution thereof over a line contact. Furthermore the centrifugal effect upon the followers at higher speeds augments the spring action which is provided to urge the followers to follow the cam relief contour. In doing this, I prefer to transmit the main portion of the feed thrust pressure upon a drill through a fulcrum with the followers mounted on the long arm of a lever to thereby further reduce the loading upon a cam and follower arrangement. Thus through a load relieving lever the cam and follower arrangement has a force advantage and also complete control over the feed thrust pressure.

By way of illustrating my invention and its use, a drill press 10 is shown in Fig. 1 in which a drill press head 11 is mounted upon a standard 12, to carry upon one side of the standard a motor 13 and upon the other side a quill 15 which is driven from the motor through the belt and pulleys 14. The quill 15 is reciprocated for feed and return movements through a rack and gear (not shown) as controlled by a manual throw or handle 16 and carries on its lower end a chuck 17 having a Morse taper that receives a shank 18 of a driller 20 embodying the invention. The driller 20 in turn is provided with an Erickson chuck 21 receiving a twist drill 22 in rotary drive relationship to cooperate upon a work piece 23 that is mounted in turn upon the table 24 of the drill press. A lubricant line 25 is provided with a flow of lubricant supplied to cool and lubricate the drill in its drilling operation. If lubricant is employed it can also serve to wash away the chips formed by the driller 20.

As more particularly shown in Fig. 2 the driller 20 comprises an outer casing composed of an upper portion 26 and a lower portion 27 which are secured together by bolts 28 and supported against rotation by an outrigger or arm 30 resting against and sliding up and down on the standard 12 during feed movement of the drill. As shown in Figs. 4, 7 and 8, the outrigger or arm 30 is secured to the upper portion 26 of the casing by being threaded thereto as indicated at 31 and locked in position by a locknut 32. The arm may be of any simple size or shape to contact a stationary part of the drill without hindering the feed traverse of the drill. The upper and lower portions 26 and 27 of the casing are cup-shaped with heat dissipating fins 33 on the outside thereof. When secured together by the bolts 28 the portions define an interior compartment within which the working parts of the device are housed protectively and lubricated. An opening 34 in the upper portion receives the drive member 35 and the wall of an opening 36 in the lower portion 27 receives in journalled relationship a driven member 37.

The drive member 35 includes the shank 18 which mates with the Morse taper 17 in the usual manner. When mated the rotary and feed drive of the spindle is transmitted to drive member 35.

5 In order to transmit the rotary drive of the drive member 35 to the driven member 37, the drive member is bored out as at 38 to a cylindrical contour and slotted at diametrical sides to the wall thereof as at 40.

10 The driven member 37 is externally grounded at its upper end to telescope into the cylindrical bore 38 of the drive member and receives a pin 41 therethrough whose outer ends extend outwardly through the slots 43 in the drive member. With this arrangement the rotary drive of the drive member 35 is directed against the pin 41 by the walls of the slot 40 and the pin 41 in turn rotates the driven member 37. The length of the slots 40 is such that the drive and driven members may be reciprocated with respect to each other.

15 The feed thrust from the drive to the driven member is transmitted through a mechanism housed in the casing which mechanism also accomplishes the reciprocation of the driven member to impart to the drill the oscillation desired as prescribed in the above mentioned Karweit application and known as the Karweit process.

This mechanism comprises two vertically spaced, substantially identical rings 42 having a cam path 20 on their inner face which includes a cylindrical dwell portion 43 (Fig. 4) and sinusoidal relief 44 of from .015 to .040 of an inch in depth extending over an arc from 40° to 60°. The rings 42 are inverted with respect to each other 25 and have their respective reliefs displaced 180° with respect to each other to define two vertically spaced cam paths with the reliefs diametrically opposite each other. These rings rest against a shoulder 45 in the upper portion 26 of the casing where they are supported against rotation by pins 46. Sufficient clearance is provided radially around the outside of the rings and between them for them to hunt slightly in 30 balancing their load to allow for certain manufacturing tolerances permitted in the mechanism.

35 Rollers 47 having cylindrical treads thereon are provided to roll against the cam tracks of the rings as supported upon journals 48 provided at 40 the top of levers 50. The rollers are held in place upon the journal by a washer assembly 51 and a pin 52 to rotate against a positioning shoulder 53 upon the levers 50.

45 The levers 50 in turn are mounted upon a carrier 54 by pins 55 which serve as fulcrums. Although levers are mounted to operate as class one levers, other classes of operation can be employed as long as the long arm of the lever carries the followers and the short arm carries the 50 main portion of the load for the fulcrum. In the particular embodiment shown the short arm is nothing more than a square contour indicated at 56 which operates almost like a cam against the outer race 57 of an end thrust frictionless bearing 58 whose inner race 60 rests upon a shoulder 61 on the driven member 37. A spacer 55 may be substituted for the frictionless bearing 58 in the embodiment shown in Fig. 2 since there is no relative rotation between the carrier 54 and the drive member 37 in this embodiment. However, the frictionless bearing is preferably illustrated since with it mounted in place the construction shown can be converted to a planetary 60 control of the carrier 54 which conversion is 70 shown in Fig. 5 as will be hereinafter described.

In positioning the oscillating mechanism favorably for its operation, a shoulder 62 upon the drive member 35 receives the inner race 63 of a frictionless bearing 64 which supports the casing portions 26 in journalled relationship upon the drive member. Below the inner race 63 a spacer 65 is mounted against which the carrier 54 rests. With this arrangement a positive linkage is provided between the drive member 18 and the driven member 37 to carry the axial end thrust or feed pressures to which the system is subjected. This linkage starts with the shoulder 62 upon the drive member and ends with the shoulder 61 upon the driven member and includes the inner race 63, the bearing 64, the spacer 65, the carrier 54, the pivot pin or fulcrum 55, the short arm 56 of the lever and the frictionless bearing 58.

This linkage is urged to maintain solid contacts throughout by a compression spring 66, one end of which rests upon the shoulder 61 formed integrally with the spacer 65 and the other end of which engages a flanged washer 68 which rests against the pin 41. The flange fits over the ends of the pin and holds the pin in position.

Rotation of the carrier 54 with the drive member 35 is established by keys 70 located in key ways 71 and 72 upon the drive member and the carrier 58, respectively, as more particularly shown in Fig. 3.

The ring members 42 are held in place by means of a washer 73 supported upon a spacer 74 which also locates the two parts of the casing with respect to each other in mutual alignment.

A seal 75 of a conventional type is provided in the bottom of the casing to prevent any loss of lubricant from the casing, the casing being filled with light oils such as #10 W. S.A.E. to the height of the pin 55 so that the carrier 54 will cause the oil to splash and bathe the followers without causing undue agitation of lubricant in the casing that would develop any appreciable heat.

From the invention thus far described it will be seen that the drill will be lifted a short distance once approximately each revolution with the embodiment described depending upon whether or not the work piece is stationary or rotated. The distance the drill is lifted is determined by the depth of the relief 44 on the ring cams 42. The depth of this relief is determined in relationship to the maximum expected feed traverse to be used with the driller and the lever ratio present so that the drill will be lifted just enough for the cutting edges to cut free from the work piece and terminate the chips being formed. As mentioned in the earlier Karweit application it is preferred that the extra distance of lift be enough to allow for deflection experienced with the drill head and to have the drill come free far enough from its work for the lubricant supplied by the lubricant nozzle 25 to bathe the cutting edges of the tool. Otherwise the distance for the lift of the drill within a minor portion of a revolution as thus provided should be kept at a minimum to reduce as much as possible the inertia moments involved in reciprocating the driven member once approximately each revolution.

Referring to Fig. 5, like parts are indicated by like numerals and the description had thereof in connection with Fig. 2 applies also to Fig. 5.

In Fig. 5 the spacer 74 is removed and the ring gear 76 of a planetary system of gearing 11 is

rigidly clamped between the two portions 26 and 27 of the casing as held against rotation by a pin 78. The keys 70 are dispensed with and the sun gear 80 of the planetary gearing is keyed to the drive member 35 through the slot 74 which will be seen extends upwardly a distance sufficient for this purpose.

This arrangement leaves the carrier 54a free to rotate as an independent body and its rotation is controlled by the planet gears 81 (Fig. 6) in relationship to the interaction therewith of the sun gear which rotates at drill speed; and the ring gear 76 which is stationary having in mind the relative gear ratio of the gearing. As mentioned in my previous application, this ratio is preferably such that a drill oscillation will occur once approximately each 1½ revolutions of the drill, the relief upon the cam being shortened sufficiently that approximately the 60% of arc provided in the other embodiment is maintained in effect for the drill in this embodiment.

In viewing Fig. 6 it will be rather apparent that although the size of the sun gear will not be varied very much, the size of the ring gear can be, and planet gears can be of different sizes to vary the periodicity of the reciprocation of the drill in relationship to its rotation.

The carrier 54a moves with the planet gears since the shafts 82 upon which they are journalled are rigidly carried by the carrier 54a, the two planet gears being located diametrically opposite each other at right angles to the followers so that the slots 83 in which the followers slide may serve as guideways for the long arms of the levers to maintain the followers at diametrically opposite points. If desired, the shoulder 61 upon the spacer 65 may be eliminated to provide a smooth surfaced spacer 65a and in lieu thereof a floating washer 84 can be provided which rests against the upper face of the sun gear 80. Oilitic washer 84 and hardened thrust washer 85 transmit the feed pressure existent between the carrier 54a and the spacer 65 through the body of the sun gear 80. In order to provide the most favorable cooperation between these washers the upper one 84 is keyed to the drive shaft while the lower one 85 is free to slip against the carrier 54a or the upper one 84, or both.

Referring to Fig. 7 an embodiment is shown in which the compression spring 100 which urges the drive member 35a and a driven member 37a towards each other is located inside the driven member for reasons of compactness. The spring 100 rests in a metal cup 101, the lower end of which engages a pin 102 rigidly carried by the drive member 35a and the other end of the spring engages a pin 103 rigidly carried by the driven member 37a. The pin 103 is freed of any restraint from the cup 101 by a slot 104. The pins are driven into place through suitably aligned openings and the pin 102 passes through longitudinally elongated slots in the driven member 37a. The follower carrier 54b in this embodiment is rigidly carried by the drive member 35a with the pins 55a supporting the levers 50a disposed below the shoulder 61a to make class two levers of them. With this arrangement a longer lever arm can be provided to support the follower 47a in engagement with ring cams 42a without sacrifice to compactness. Veins 105 are provided at the periphery of the carrier 54b and the casing 39a is provided with a cylindrical wall 106 which serves as a shroud for the fan by which air is drawn down through inlets 107 in the upper

part of the casing and forced downwardly from the shroud 106 towards the work.

The ring cams 42a are supported loosely in place by bolts 46a within a recess 108 of a cap 110 which floats loosely upon a conical surface 111 that is provided upon the upper face of a flange 112 formed integrally with the drive member 35a. The carrier member 54b has an external flange 113 at the top thereof which runs against the bottom face of the ring cams 52a with the upper face of the ring cams engaged by a lubricant washer 114 disposed below the flange 112. With this arrangement the ring cams 42a are positioned with respect to the drive member 35a and since the ring cams 42a carry the casing 39a through bolts 46a, the whole assembly is a semi-floating assembly which does not provide any thrust loads that require conventional frictionless or end thrust bearings, the oscillating load being dissipated radially against ring cams through rolling contacts provided by the rollers 47a against the face of the cam. The only end thrust carried by the relative members other than through the pin 55a against the reaction of the cam at the follower assembly is the weight of the casing and since this is negligible, the device thus provided when operated at high speeds runs comparatively cool.

The cap 110 is provided with an oil reservoir 115 which is filled with waste or felt 116 and has a wick 117 leading therefrom to discharge oil in minute quantities down through a drip opening 118 in the washer 114 from the bottom of which the oil is picked up by the rollers 47a as they pass thereover in their rotation.

Having thus described the invention in its several embodiments it will be seen how the end thrust load is dissipated in a radial direction that is entailed with oscillating the drill according to the Karweit process. Furthermore the increasing centrifugal force engendered by the followers with higher speeds counteracts the tendency for the follower to float over the relief in the cam which also increases at high speeds. Thus a lighter spring can be used to urge the drive and driven member toward each other. Not only this, but the moments of inertia involved in reciprocating the elements are greatly reduced.

Consequently, although several preferred embodiments have been disclosed and described herein it will be readily apparent to those skilled in the art from the description and discussion herein made, that various and further modifications can be made without departing from the spirit of the invention, the scope of which is commensurate with the appended claims.

What is claimed is:

1. In a device of the class described having a housing and a drive shaft and a drill carrying driven shaft mounted therein for simultaneous rotation and relative reciprocation, an annular cam member supported upon the housing and having an inside cam path thereon with a relief therein occupying a minor portion of the circumference, a fulcrum member supported upon the drive shaft and rotatable therewith, a lever mounted upon one arm thereof engaging the cam, and means for transmitting movement of the other arm of the lever to the driven shaft whereby the driven shaft is reciprocated axially once each time said follower moves across said relief a distance sufficient to comminute chips developed by the drill when the drill is in cutting position.

2. In a device of the class described having

drive and driven shafts supported for simultaneous rotation and relative reciprocation, said driven shaft being adapted to carry a drill, a pair of annular cam members supported upon the housing and each having an inside cam path thereon with a single relief in each occupying an arc of less than 180°, fulcrum members supported upon the drive shaft and rotatable therewith, levers mounted respectively upon said fulcrum members and each having a follower upon one arm thereof, said followers respectively engaging said cam paths, and means for transmitting movement of the other arm of each lever to the driven shaft whereby the driven shaft is reciprocate axially once each revolution a distance sufficient to comminute chips developed by the drill when the drill is in cutting position.

3. In a device of the class described having drive and driven shafts supported for simultaneous rotation and relative reciprocation, said driven shaft being adapted to carry a drill, an annular cam member supported upon the housing and having an inside cam path thereon with a relief therein occupying a minor portion of 360°, a follower, means for supporting the follower in contact with the cam path, means for rotating the supporting means in stepped relation with the drive shaft and means controlled by the follower and cam member for oscillating the driven shaft in stepped relation with the drill rotation a distance sufficient to comminute chips developed by the drill.

4. The apparatus called for in claim 3 including a blower for moving air over and in direct contact with the follower and cam.

5. In a device of the class described having a stationary element and a drive shaft and a drill carrying driven shaft journaled for simultaneous rotation and relative reciprocation, a cam and follower assembly including an annular cam member supported on the stationary element and having a radial cam path thereon with a relief therein occupying a minor portion of the circumference, a follower member supported upon the drive shaft and rotatable therewith to cooperate with the cam member, means for urging the members into contact with each other, and means for translating movement of the follower member to oscillating movement of the driven shaft whereby the driven shaft is repeatedly reciprocated axially a distance sufficient to comminute chips developed by the drill, centrifugal force augmenting said urging means at higher shaft speeds.

6. In a device of the class described having a stationary element and a drive shaft and a drill carrying driven shaft journaled for simultaneous rotation and relative reciprocation, a cam and follower assembly including an annular cam member and a follower member cooperating with each other for relative radial movement with the cam having relief therein occupying an arc of less than 180°, one of said members being carried by the stationary element and the other member being supported upon the drive shaft and rotatable therewith, means for translating the relative radial movement to an axial movement including a lever, and means controlled by said lever for reciprocating repeatedly the driven shaft axially in stepped rotation therewith a distance sufficient to comminute chips developed by the drill.

7. The combination called for in claim 6 where in said translating means reduces the distance of

axial movement to less than the distance of the relative radial movement.

8. In a device of the class described having a housing and drive shaft and a drill carrying driven shaft mounted therein for simultaneous rotation and relative reciprocation, the combination of an annular cam member supported upon the housing and having an inside cam path thereon with a relief therein occupying an arc of approximately 60°, a fulcrum member supported upon the drive shaft and rotatable therewith, a lever mounted upon the fulcrum member and having a follower upon one arm thereof engaging the cam member, and means for transmitting movement of the other arm of the lever to the driven shaft whereby the driven shaft is reciprocated axially once approximately each revolution a distance sufficient to comminute chips developed by the drill when in cutting position.

9. In a device of the class described having a housing and a drive shaft and a drill carrying driven shaft mounted therein for simultaneous rotation and relative reciprocation, an annular cam member supported upon the housing and having a radially disposed cam path thereon with a relief therein occupying an arc less than 180°, a ring gear carried by the housing, a follower device cooperating with the cam member including a lever and a cam follower on one arm of the lever, a planet gear carried by the follower device in mesh with the ring gear, a fulcrum member supported upon the drive shaft and rotatable therewith, means for translating radial movement of the lever to an axial oscillation of the driven shaft whereby the driven shaft is

reciprocated axially a distance sufficient to comminute chips developed by the drill, and a sun gear in mesh with the planet gear and driven from the drive shaft.

- 5 10. In a device of the class described having a stationary element, and a drive shaft and a drill carrying driven shaft journaled for simultaneous rotation and relative reciprocation, the combination of an annular cam member supported upon the stationary element and having a radial cam path thereon with a relief therein occupying an arc of less than 180°, a follower device cooperating with the cam path including a lever having a follower upon an arm thereof engaging the cam path and means for translating the cam and follower action to an oscillation of the driven shaft whereby the driven shaft is reciprocated axially a distance sufficient to comminute chips developed by the drill, a differential transmission interconnecting the drive shaft and the stationary element including an intermediate gear carrying said follower device whereby the reciprocation of the drill is recurrent in stepped relationship with the rotation of the drill.
